CONTROL FOR POWER DRIVEN
MECHANISMSRalph E. Lamberton, Michigan City, Ind., assignor
to Sullivan Machinery Company, a corporation
of Massachusetts

Application February 21, 1941, Serial No. 379,943

25 Claims. (Cl. 254—187)

My invention relates to prime mover driven apparatus of the type in which a plurality of power operated mechanisms are selectively caused to perform their working functions by power from the prime mover. More particularly, it relates to combined pumping and hoisting mechanisms driven by a common source of power and having improved means for selectively controlling the pumping of fluid by the pumping apparatus and the doing of work by the hoist.

In construction work a source of compressed air for the operation of pneumatic tools is commonly necessary, and a hoist is also often needed. To provide separate hoist and compressor units, each with its own prime mover, is relatively expensive. To provide a complete compressor unit and an air operated hoist is somewhat less expensive, but the size of such a hoist might be somewhat limited if it were to be operated by air supplied by the compressor. There might be less advantageous possibilities of utilizing air driven tools and the hoist at the same time than are provided with my invention, and the overall efficiency would be reduced as compared with a system in which direct drive of the hoist from a prime mover is employed. If, however, as my invention makes possible, a single prime mover be utilized for the direct drive of the hoist and for the direct drive of a compressor, and provision be made to make available substantially the full power of the prime mover at the hoist and stored air can be utilized, as in the preferred form of my invention, for tool operation while hoisting is being done, a very satisfactory system can be had; and if coordinated control of the compressor and hoist be, as in my invention, arranged so that a complicated system of selective clutches and special arrangements of engine relative to the hoist and compressor be avoided, very desirable equipment is provided. The location of a radiator at one end of the unit with an internal combustion engine adjacent the radiator and with a compressor aligned with and driven directly by the engine—a very common and practical form of apparatus—makes drive of the hoist through the compressor drive shaft a most practicable arrangement if, as according to my invention, means for unloading the compressor when the hoist is driven is provided. And if, as in my invention, coordinated control be provided so that, regardless of whether the compressor be loaded by its discharge pressure responsive control mechanism when hoist drive is to be initiated, it can be positively unloaded when the load on the hoist is imposed on the driving motor, a most

satisfactory hoist and compressor unit will be obtained. It will be understood that other power operated devices than a hoist can be provided, and that the compressor is merely illustrative of the broad class of pumping devices, and that liquid pumps or vacuum pumps as well as a compressor come within the broad scope of my invention.

One object of my invention is to provide an improved apparatus in which a pumping device and a separate power driven mechanism may be mounted, for example, on a common base structure and be provided with improved means for controlling the operation of the mechanisms selectively by a single power unit. Another object of my invention is to provide in a combined pumping apparatus and hoisting mechanism an improved means for effecting unloading of the pumping apparatus during operation of the hoist. Still another object is to provide an improved piece of apparatus including a compressor connected for continuous drive by a prime mover, a hoist optionally driven through the drive shaft of the compressor, means for controlling the connection of the hoist for drive, and means for interrupting the pumping of fluid by the pump when the hoist is connected up for drive. A further object is to provide improved control means for separate power driven mechanism whereby the load of one of the mechanisms is reduced simultaneously with the connection of another for drive by a power unit which supplies power for the operation of both mechanisms. Still another object is to provide a compressor connected continuously in driving relation with a power unit, a hoist, and improved means for selectively controlling the connection of the hoist in driving relation with an engine and a loading of the compressor so that on connection of the hoist in driving relation with the engine the compressor will be unloaded. Other objects and advantages will appear in the course of the following description.

In the accompanying drawings in which for purposes of illustration one form and two modifications which the invention may assume in practice have been shown.

Fig. 1 is a side elevational view, with parts broken away, showing a preferred embodiment of the invention.

Fig. 2 is a plan view, with parts broken away, of the mechanism shown in Fig. 1.

Fig. 3 is an enlarged view with parts in vertical section and parts in elevation, taken on the line 3—3 of Fig. 2.

Fig. 4 is an enlarged view in elevation, taken on line 4—4 of Fig. 2.

Fig. 5 is an enlarged sectional view through a compressor cylinder, taken on the plane including the axis of the cylinder.

Fig. 6 is an enlarged vertical sectional view through a valve for controlling compressor unloading, the section being taken on the line 6—6 of Fig. 2.

Fig. 7 is a view similar to Fig. 6, showing the valve in a different position.

Fig. 8 is a detail sectional view through a manually operable valve for controlling the venting of the compressor discharge line.

Fig. 9 is an enlarged side elevational view, similar to that of Fig. 4, showing a modified form of the invention.

Fig. 10 is a side elevational view of a portion of the apparatus showing another modification of the invention.

Fig. 11 is a fragmentary view in plan of a portion of the compressor and the control system thereof as utilized in the modified form of the invention shown in Fig. 10.

In the preferred embodiment of the invention shown in Figs. 1 to 8 inclusive, an engine 1, herein shown as of the gasoline type, though it will be obvious that it may assume many other forms, pumping apparatus in the form of a compressor 2, and a further power operated device herein in the form of a hoist 3, are mounted on a common base structure generally designated 4 of any suitable type and shown herein as comprising spaced parallel skids 5 adapted for support on and sliding over the ground and connected by cross members 6. Mounted on the base between the compressor and the hoist are control means, generally designated 7, for controlling the connection of the hoist in driving relation with the engine, and associated with this control means is a manually operated lever 8 for operating the control means 7 whose movements also control the pumping operation of the compressor, as will shortly be described. Surrounding the engine and the compressor is a casing 9, and mounted on the base structure adjacent the engine is a radiator 10 containing cooling fluid for the engine.

As above noted, the engine is shown as of the internal combustion type, and is arranged with its power shaft extending longitudinally of the base structure, and the engine is provided with a throttle device 11 which is controlled by manually operated and automatically operated means, generally designated 12, that will shortly be described more in detail.

The compressor 2 shown herein is of the multi-cylinder, single stage type having cylinders 14 and 15 extending radially from a crankcase 16, and the compressor crankshaft, a portion of which is shown at 17, is arranged in alignment with the power shaft of the engine and shown as driven directly thereby. It will of course be evident that it may be connected through a clutch or in any other suitable member to the engine shaft. The shaft 17 is connected, as shown in Fig. 3, through a coupling 18 to a shaft 19 which is shown journaled in ball bearings 20 supported by a frame 21 mounted on the base structure 4. A fan 22 is mounted on a bracket 23 connected to the compressor crankcase, and is driven by a belt 24 engaging a pulley 25 on the compressor crankshaft for circulating cooling air through the casing 9 about the compressor and the engine.

The compressor cylinders are identical in construction, and each comprises, as shown in Fig. 75

5, a cylinder member 26 having a bore 27 within which a piston 28 is reciprocated, through a connection not shown, by the crankshaft 17. Formed in the cylinder member coaxial with the bore 27 is a larger bore 29 which receives a valve mechanism generally designated 30 and a cylinder head 31. The cylinder head is attached to the cylinder as by bolts 33 and clamps the valve mechanism firmly in position against a shoulder 34 at the junction of the bores 27 and 29. Connected to the side of the cylinder member as by bolts 35 is a conduit 36 at whose outer end an air filter 38 is arranged and whose other end communicates with an inlet passage 39 in the cylinder member. The passage 39 communicates with another inlet passage 41 formed in the cylinder head, and the latter passage opens under the control of an inlet valve 43 into the cylinder bore. A discharge valve 44 controls the flow of compressed air from the cylinder to a passage 45 leading to a discharge conduit 47. The discharge conduits from the cylinders 14 and 15 are connected to a common conduit 49 which delivers the compressed air to a storage tank or receiver 50 supported above the base structure by support members 51 and 52.

Unloading means of the inlet valve opening type is provided for each of the compressor cylinders. These unloading means are each generally designated 54, and each includes members 56 and 57 and a plate 58 attached to the top of the cylinder head of its respective cylinder by bolts 59. Formed between the members 56 and 57 is a chamber 61, and a flexible diaphragm 63 clamped between the members 56 and 57 is movable within the chamber. A plunger 65 projects through an opening in the plate 58 into the chamber 61, and arranged for movement by the plunger is a plate 66 which is received in a recess 67 formed in the cylinder head beneath the plate 58. Attached to the plate 66 are rods or fingers 69 which extend through openings 70 in the cylinder head into the intake passage 41 and are engageable at their lower ends with the inlet valve 43 to move the latter from its seat and unload the compressor cylinder when the plate 66 is moved downwardly in the recess 67. A spring 72 shown herein as a bowed plate type spring acts between the bottom of the recess 67 and the plate 66 to hold the plate normally in its upper position with the plunger 65 held against the diaphragm 63. A guide pin 73 fixed to the cylinder head 31 extends through an opening in the spring 72 into a recess 75 in the plate 66 to guide the moving parts. Surrounding the plunger just above the plate 58 is a packing 77 sealingly engaging the plunger to prevent the passage of pressure fluid from the chamber 61 to the recess 67. A spring 78 rests upon the packing ring 77 and acts against the lower surface of the diaphragm 63 and holds the latter normally in its raised position.

It will be observed that the plunger 65 may be moved to its lower position to effect opening of the inlet valve and unloading of the compressor cylinder by admitting pressure fluid to the chamber 61 beneath the diaphragm so that it acts directly on top of the plunger, or by admitting pressure fluid to the space above the diaphragm so that the diaphragm itself will be pressed downwardly and move the plunger 65 ahead of it. To effect automatic unloading of the compressor and reloading thereof in accordance with compressor discharge pressure variations, there are provided conduits 80 opening into the chambers 61 beneath the diaphragms

63, and these conduits are connected to a common conduit 82 which is normally connected through a device 83, which permits free flow of pressure fluid toward the unloading plungers 65 but delays venting of fluid from these plungers, to a pilot valve 84, which may be of any suitable type and which is herein illustrated as a so-called RC pilot valve, connected in the compressor discharge conduit 49. This pilot valve is operative upon the attainment of a predetermined maximum desired compressor discharge pressure to supply fluid past the device 83 to the conduit 82, and upon a drop in pressure to a predetermined minimum value, to vent the conduit 82.

The mode of operation of the automatic pressure responsive unloading system may be summarized as follows: The pilot valve 84 is responsive to a predetermined maximum pressure in the discharge conduit to supply fluid at receiver pressure from this conduit through the device 83, and through the conduit 82 and conduits 89 to the chambers 61 beneath the diaphragm 63, where it acts on the plungers and moves them to their unloading positions. On a predetermined drop in receiver pressure below the predetermined maximum pressure mentioned, the pilot valve 84 operates to vent pressure fluid from the chambers 61 through the conduits 88, the conduit 82 and past the delay device 83 to atmosphere. The delay device is of a well known construction and limits the rate of flow of pressure fluid from the unloading means so that reloading takes place a material interval after the pilot valve responds to the attainment of the minimum desired predetermined receiver pressure to initiate reloading, but when the pilot valve opens to supply pressure fluid to the unloading devices, the delay valve device 83 permits the free passage of this fluid and unloading takes place substantially immediately.

To effect unloading of the compressor when the same may be operating loaded and it is desired to connect the hoist for drive by the engine, conduits 86 are provided opening into the chamber 61 above the diaphragm 63, and these conduits are connected to a common conduit 87 which opens into a bore 88 in a valve casing 90, as shown in Figs. 6 and 7. Arranged in the crank case of the compressor is a lubricant pump, not shown, for supplying lubricant to parts of the compressor mechanism, and connected to this lubricant pump is a conduit 92 which opens into the bore of the valve casing 90 at a point angularly spaced from the connection of conduit 87. A conduit 93 also opens into the bore of the valve casing, this last mentioned conduit at a point spaced from the conduit 87 in a direction opposite that of the conduit 92, and the conduit 93 leads back to the compressor crank case and is adapted to return oil thereto. A valve 95 is rotatably mounted in the bore 88 of the valve casing and is provided with a groove 96 for connecting the conduits 87 and 92 when it is in one of its limiting positions, and for connecting conduits 87, 93 when it is in its other limited position. An arm 98 is connected to the valve 95 and a rod 99 connects the end of the arm to the manually operated lever 8. From this it will be evident that when the manually operated lever 8 is moved to connect the hoist for drive by the engine, oil will be delivered through the conduit 92, the groove 96, the conduit 87 and the conduits 86 to act upon the tops of the diaphragms 63 and to force these diaphragms downwardly thereby forcing

downward also the plungers 65, and so effecting unloading of the compressor.

Referring to the control means 12 for the throttle device 11 it will be noted that a rod 102 is connected at one end to the throttle and is connected at its other end to an arm 103 mounted for pivotal movement at 104. Suitable pressure responsive means indicated at 105 are provided for effecting a swinging of the arm 103 about its pivot to move the rod 102 in a direction to close the throttle when pressure fluid is supplied thereto. A conduit 105' leading from the pressure responsive device 105 opens into the delay device 83 at a point having direct communication with the pilot valve and conducts pressure fluid to the pressure responsive means controlling the throttle immediately on response of the pilot valve to the predetermined maximum pressure in the discharge conduit. A lever 106, pivotally mounted between its ends, operatively engages, at one of its ends, the rod 102, and is connected at its other end to a rod 107 which is connected to a lever 108 that may be manually operated to open or close the throttle.

If the pressure in the compressor discharge conduit 47 is high enough to cause the pilot valve 84 to open, pressure fluid will be supplied to the chamber 61 beneath the diaphragm to effect compressor unloading and at the same time pressure fluid will be supplied to the throttle control means 12 to effect a closing of the throttle and a slowing down of the engine. If no other provisions were made than have so far been described, and if the lever 8 were moved at this time to a position to connect the hoist in driving relation with the engine, the load of the hoist might be sufficient to stall the engine since pressure fluid would continue to be supplied to the control means 12 for holding the throttle in relatively closed position until the pressure in the discharge conduit dropped to a value at which the pilot valve would move to its venting position. After movement of the lever 8 to its hoist-driving position, oil is pumped to the chamber 61 above the diaphragm, but it may not force the diaphragm downwardly against the pressure of the fluid beneath the diaphragm and the spring 78 because the pressure at which the oil is delivered is much lower than the pressure in the discharge conduit when unloading takes place, and the area of the diaphragm exposed to the oil is somewhat reduced when the diaphragm is held against the upper wall of the chamber 61. Assuming that pressure fluid is used from the receiver and causes the pressure in the discharge conduit to drop to a point at which the pilot valve moves to its venting position, then pressure fluid is immediately vented from the control means 12 and the motor, if it is still running, is speeded up, but pressure fluid is slowly vented from beneath the diaphragm and for a time the compressor is held unloaded. When the pressure beneath the diaphragm drops to a value at which the compressor reloads, it may still be high enough to hold the diaphragm in its upper position against the pressure of the oil. If this is so the compressor will reload and may cause the pressure in the discharge line to increase to a point at which the pilot valve operates again to supply pressure fluid to the unloading means and to the carburetor control means before the diaphragm is moved by the oil to a position for unloading the compressor. Operation of the mechanism in the above manner would mean that the hoist and the compressor unloaded may be driven by the en-

gine while running at a very slow speed, or that the hoist and the compressor loaded may be driven by the engine running at a high speed.

It is therefore desirable that the compressor be unloaded and held unloaded whenever the lever 8 is in a position connecting the hoist in driving relation with the engine, and that the engine operate at a speed sufficient to carry the load of the hoist. To assure such operation there are provided means, generally designated 109, for venting the discharge conduit 47 immediately the hoist mechanism is connected to the engine. To prevent pressure fluid from escaping from the receiver through the vented discharge conduit, there is provided a check valve 110 in the conduit 49, and this check valve permits fluid to flow toward the receiver but prevents fluid from flowing in the opposite direction. The vent control means 109 comprises, as shown in Fig. 8, a valve casing 111 having its interior connected by a conduit 112 to the discharge conduit 47, and connected through an opening 113 to atmosphere. A septum 114 divides the interior of the casing and is provided with an opening 115 controlled by a valve 116. A valve stem 117 projects from the valve through a plug 118 secured to the casing, as shown in Fig. 8, and is attached to a cylinder member 119. A rod 120 is attached at one of its ends to an arm 121 carried by the valve 95 as shown in Fig. 4, and at its other end is a piston 122 reciprocably contained within the cylinder member 119. A cap 123 is threaded on the cylinder member, and springs 124 and 125 positioned within the cylinder member act on opposite sides of the piston and against the cylinder member and the cap 123, respectively, for holding the piston normally in a central position between the ends of the cylinder member. It will be seen that when the lever 8 is moved to connect the hoist, the valve 116 will be moved to uncover the opening 115 by reason of its connection to the valve 95 through the mechanism described above, and pressure fluid is vented from the compressor discharge conduit 47 through the conduit 112, casing 111, opening 115 and the opening 113 to atmosphere, but the pressure in the receiver is retained since the check valve 110 prevents the escape of fluid from the receiver to the discharge conduit. With reduced pressure in the discharge conduit the pilot valve will be in its venting position, the carburetor control means 12 will be in a position to open the carburetor and speed up the engine, and any pressure fluid beneath the diaphragm of the compressor unloading means will be vented so that oil pumped to the top of the diaphragm will move the latter down and effect unloading of the compressor. When the lever 8 is moved to disconnect the hoist, the valve 116 is closed, pressure is built up in the discharge conduit, and the mechanism operates automatically to load and unload the compressor with speeding up and slowing down of the engine as previously described.

Now referring to the control means 7, as shown in Fig. 3, for controlling the connection of the hoist in driving relation with the engine, it will be noted that a plate 126 is fixed in any suitable manner, as by welding or by a keyed connection, to the shaft 19 and has attached thereto, as by bolts 127, an annular shaped member 128. Attached to the member 128, as by screws 129, is a ring-shaped member 130 adapted to be clamped between a plate 131 on a hoist driving shaft 132 and a cooperating plate later described. The hoist driving shaft 132 is in alignment with the

shaft 19 and has an end 133 of reduced diameter that is journaled in a ball bearing 134 fixed in the open center of the annular member 128. The opposite end of the shaft 132 has keyed there-
5 to a chain sprocket 135, and the portion of the shaft adjacent the chain sprocket is journaled in a bearing 136 supported within the end wall of a casing 137 which encloses the parts of the control means 7 and is mounted on the 10 base structure 4. Formed on a hub on the member 131 are teeth 138, and an annular shaped member 139 is provided with teeth around its inner periphery which interlock with the teeth 138 so as to prevent relative rotation between the 15 members 131 and 139, but permit bodily movement of the member 139 longitudinally of the shaft 132 and relative to the member 131 for effecting a clamping of the clutch element 130 carried by the member 128 between the members 131 and 139. Springs 140 between the members 131 and 139 continuously urge them apart to release the clutch member 130. Threaded on the hub of the member 131 is a ring 141 having pivotally mounted thereon a plurality of members 20 142 (of which but one is shown), each of which is provided with an arm portion 143 for engaging a rear abutment surface on the member 139 and a rearwardly extending arm portion 144 that is connected by a link 145 to a member 146 slid-
25 ably mounted on the shaft 132. Formed on the member 146 is a flange portion 147, and engaging this flange portion is a shipper ring 148 that is operatively connected to a shipper arm 149 clamped on a shaft 150 extending transversely of the shaft 132. The shaft 150 is pivotally supported by the walls of the casing 137 and has attached to one of its ends the manually operated lever 8. It will be seen that on throwing that the lever 8 in a counterclockwise direction, as viewed 30 in Fig. 4, the member 146 will be actuated through the shipper arm 149 and the shipper ring 148 to the left, causing the links 145 to swing the members 142 about their pivots and move the member 139 in a direction to clamp the ring 130 between it and the plate 131, thereby connecting the shaft 132 in driving relation with the shaft 19. On throwing the lever 8 in an opposite direction, the members 142 are moved away from the member 139 and the springs 140 force the members 131 and 139 apart releasing the clutch and disconnecting the shaft 132 from driving relation with the shaft 19.

The hoist 3 shown herein is mounted on the rear of the base structure 4 with its drum 152 arranged to rotate on an axis extending transversely of the base structure. A chain 153 engages the chain sprocket 135 on the shaft 132 and drives a chain sprocket, not shown, on a shaft 154 which is connected through suitable gearing, not shown, for driving the drum 152. Suitable means are provided for controlling the operation of the drum and are shown here as including operating levers 155, 157 and 158. The lever 155 is connected through a link 160 to a shaft 161 which effects operation of a clutch, not shown, controlling the drive of the drum. The lever 157 is connected through a link 162 to a shaft 163 on which a dog 164 is fixed and is movable by the shaft 162 into engagement with teeth 166 on the drum for locking the latter against rotation in an unwinding direction. The lever 158 is connected through a link 168 to a shaft 169 and controls the operation of a brake, not shown, for breaking the rotation of the drum. It will be noted that, since control of

the hoist is effected by the levers last described after the control lever 8 has been operated to connect shaft 132 to shaft 19, the other control mechanism will have had time to become operative before the hoist load is applied to the engine.

The mode of operation of the mechanism described may be briefly summarized as follows. Assuming that it is desired to compress air for delivery to the receiver, the lever 8 will be swung into the position shown in Fig. 4 to disconnect the hoist drive shaft 132 from driving relation with the engine, to effect a closure of the valve 116 cutting off the venting of the compressor discharge conduit, and to move the valve 95 into the position shown in Fig. 6 so that any liquid in the chambers 61 above the diaphragms 63 of the compressor unloading means may be vented to the crankcase of the compressor. The spring 78 of the unloading means forces the diaphragm 63 to its upper position, and, if the space in the chamber 61 beneath the diaphragm is vented to atmosphere, as will be the case if the pressure in the receiver is low enough so that the pilot valve 84 assumes its venting position, the plunger 65 will be moved to its upper position by the spring 72 to lift the fingers 69 from the inlet valves and permit normal operation of the latter. The engine then drives the compressor loaded at a speed which may be varied by adjustment of the throttle by the manually operated lever 103. If the pressure in the receiver builds up to the maximum value for which the pilot valve 84 is adjusted, the latter operates and air under pressure flows immediately through conduit 105' to operate the pressure responsive means of the throttle control means 12 and effect a slowing down of the engine. Pressure fluid also flows immediately past the delay valve 83 to the chamber spaces beneath the diaphragms where it acts on the tops of the plungers 65 and moves them to positions unloading the compressor. If the pressure in the receiver again drops to the lower operating pressure of the pilot valve 84, pressure fluid is vented freely from the pressure responsive means of the carburetor control means 12 causing the engine to speed up, and is vented slowly from the space in the chamber 61 beneath the diaphragm 63 so that the compressor is reloaded after the motor has speeded up.

If it is desired to use the hoist 3, the lever 8 is swung in a counterclockwise direction from the position shown in Fig. 4. This causes the rod 99 to move the valve 95 into the position shown in Fig. 7 for supplying oil under pressure to the upper side of the diaphragm 63, and effects an opening of the valve 116 for venting pressure fluid from the discharge conduit 47. With the discharge conduit vented the pilot valve moves to a position venting the throttle control means 12 and the spaces beneath the diaphragms 63. The engine speeds up and the pressure of the oil on top of the diaphragms forces the latter to their lower positions, moving with them the plungers 65 for unloading the compressor. The swinging of the lever 8 in a counterclockwise direction also causes a rotation of the shaft 150 which moves the shipper arm 143 in a direction to effect a clamping of the clutch ring 130 and a connecting of the shaft 132 in driven relation with the engine 1. As the shaft 132 is caused to rotate, the chain sprocket 135 on the end of the shaft 132 drives the chain 153 which in turn drives the shaft 154

and the hoist drum 152 may then be turned through suitable gearing and a clutch, not shown.

In the modification of the invention shown in Fig. 9 means are provided for blowing down the receiver when the lever 8 is moved to a position for connecting the hoist in driving relation with the engine. With the receiver blown down the pressure in the compressor discharge line will of course be approximately atmospheric, and the pilot valve will move to its venting position to vent pressure fluid from the carburetor control means and from the spaces beneath the diaphragms of the compressor unloading means. On supplying fluid under pressure to the spaces above the diaphragms the compressor will be unloaded and, since this supply will be continued as long as the lever 8 is in its hoist-connecting position, the hoist and the compressor unloaded will be driven by the engine at a high speed.

The structure in this modification is the same as that of the preferred form except that the venting means for the compressor discharge line, as shown in the preferred form, is eliminated, and means for blowing down the receiver is provided. Due to the similarity of construction only a portion of the apparatus need be shown, and like parts will be numbered the same as in the preferred form. In this construction the receiver 59 is connected by a conduit 172 to a valve device 173, and a conduit 174 connects the valve device 173 to atmosphere through an opening in a plate 175 supported by the skids 5. The valve device is normally closed but a valve actuating plunger 176 is engageable by a cam portion 177 on a lever 178 for opening the valve device on actuation of the lever. Fixed to the lever 8 is a projecting member 180 for engaging the lever 178 and moving the latter to effect an opening of the valve device 173 and a venting of the compressor when the lever 8 is moved in a counterclockwise direction to connect the hoist in driving relation with the engine through the clutch control means 7. On moving the lever 8 in a counterclockwise direction the valve 95 is moved through the rod 99 and the arm 98 to a position connecting the conduits 87 and 92 so that oil is supplied under pressure from the compressor crankcase for effecting an unloading of the compressor as in the preferred form of the invention. When the lever 8 is moved in a clockwise direction to disconnect the hoist, the valve device 173 closes cutting off the escape of fluid from the receiver, and the valve 95 is moved to a position connecting conduits 87 and 93 for venting oil from the compressor unloading means.

The modification of the invention shown in Figs. 10 and 11 is like that of the preferred form except that no means are provided for venting the compressor discharge conduit 47 when the hoist is connected in driving relation with the engine. As long as the pressure in the receiver 59 is below the maximum operating pressure of the pilot valve 84 the compressor unloading means below the diaphragms will be vented to atmosphere, and as soon as the lever 8 is moved to its position for connecting the hoist in driving relation with the engine, oil supplied through the conduits 92 and 87 to the unloading means above the diaphragms will cause the compressor to be unloaded. When the lever 8 is moved to a position to disconnect the hoist the oil will be vented from the unloading means through conduits 87 and 93 to the compressor crankcase, and the compressor reloads and pumps fluid to the receiver until the pressure reaches that at which the pilot

valve opens to supply pressure fluid through the delay valve 83 and the conduits 82, 80 to the unloading means, and through conduit 105 to the carburetor control means for slowing down the engine. While this form lacks something of the nicety and certainty of control of the first form, it is effective within ordinary operating needs.

As a result of this invention it will be noted that there is provided an improved means for selectively connecting the load of separate power driven mechanisms in driving relation with a single power unit. It will further be noted that there is provided a compressor connected continuously in driving relation with a power unit, a separate power driven mechanism connectible in driving relation with the power unit, and improved means for unloading the compressor while the power driven mechanism is being driven by the power unit. It will also be noted that there is provided a compressor having improved automatically controlled and manually controlled unloading means, a hoist, and means for controlling the connection of the hoist in driving relation with the compressor crankshaft and simultaneously effecting an operation of the manually controlled unloading means. Other advantages of the invention will be clearly apparent to those skilled in the art.

The improved unloading means per se disclosed in this application is being claimed in my co-pending application, Ser. No. 448,615, which is a continuation-in-part of the present application.

While there are provided in this application a preferred form and two modifications which my invention may assume in practice, it will be understood that this form and modifications are shown for purposes of illustration and that the invention may be further modified and embodied in various other forms without departing from its spirit or the scope of the appended claims.

What I claim as new and desire to secure by Letters Patent is:

1. In combination, a power unit, a compressor connected for drive by said power unit, unloading means for said compressor, a power driven mechanism adapted to be driven by said power unit, means for controlling the connection of said power driven mechanism in driven relation with said power unit, and means operatively connected to said last mentioned means and operative simultaneously therewith for controlling said unloading means.

2. In combination, a power unit, a compressor connected for drive by said power unit, unloading means for said compressor, a power driven mechanism adapted to be driven by said power unit, means for connecting said power driven mechanism in driven relation with said power unit, and means operatively connected to said last mentioned means and operative simultaneously therewith for effecting an unloading operation of said unloading means when said power driven mechanism is connected in driven relation with said power unit.

3. In combination, a power unit, a compressor connected for drive by said power unit, fluid actuated unloading means for unloading said compressor on the supply of fluid thereto, a power driven mechanism adapted to be driven by said power unit, means for connecting said power driven mechanism in driven relation with said power unit, and means operatively connected to said last mentioned means and operative simultaneously therewith for supplying actuating fluid

to said unloading means when said power driven mechanism is connected in driven relation with said power unit.

4. In combination, a power unit, a compressor connected for drive by said power unit, fluid actuated unloading means for unloading said compressor on the supply of fluid thereto, a power driven mechanism adapted to be driven by said power unit, a clutch for controlling the connection of said power driven mechanism in driven relation with said power unit, a valve for controlling the supply of actuating fluid to said unloading means, means for controlling at will the operation of said clutch, and means actuated automatically upon the movement of said clutch for effecting an operation of said valve.

5. In combination, a power unit, a compressor connected for drive by said power unit, fluid actuated unloading means for unloading said compressor on the supply of fluid thereto, a power driven mechanism adapted to be driven by said power unit, a clutch for controlling the connection of said power driven mechanism in driven relation with said power unit, a valve for controlling the supply of actuating fluid to said unloading means, means for controlling at will the operation of said clutch, and means actuated automatically upon the movement of said clutch for effecting an operation of said valve, said manually operated means and said last mentioned means being arranged for effecting simultaneously an operation of said clutch for connecting said power driven mechanism in driven relation with said power unit and the opening of said valve to supply fluid to said unloading means.

6. In combination, a power unit, a compressor having its crankshaft connected for drive by said power unit, unloading means for said compressor, a hoist adapted to be driven by said power unit, a clutch means for controlling the connection of said hoist in driven relation with said power unit, and means operatively connected to said clutch means and operative simultaneously therewith for controlling said unloading means.

7. In combination, a power unit, a compressor having its crankshaft connected for drive by said power unit, hydraulic unloading means for said compressor, a hoist adapted to be driven by said power unit, clutch means for connecting said hoist in driven relation with said power unit, valve means for controlling the supply of liquid under pressure to said unloading means, manually operated means for controlling the operation of said clutch, and means operatively connected to said clutch and operating simultaneously therewith for controlling said valve means.

8. In combination, a power unit, a compressor having its crankshaft connected for drive by said power unit, fluid actuated unloading means for said compressor, means operative at a predetermined compressor discharge pressure for supplying operating fluid to said unloading means, a power driven mechanism adapted to be driven by said power unit, manually operated means for controlling the connection of said power driven mechanism in driven relation with said power unit, and means operatively connected to said last mentioned means and operative simultaneously therewith for supplying fluid to said unloading means when said power driven mechanism is connected in driven relation with said power unit.

9. In combination, a power unit, a compressor having its crankshaft connected for drive

by said power unit, hydraulic and pneumatic unloading means for said compressor, means operative at a predetermined compressor discharge pressure for supplying gaseous fluid to said unloading means, a power driven mechanism adapted to be driven by said power unit, manually operated means for controlling the connection of said power driven mechanism in driven relation with said power unit, and means operatively connected to said last mentioned means and operative simultaneously therewith for controlling the supply of liquid to said unloading means.

10. In combination, a power unit, a compressor having its crankshaft connected for drive by said power unit, a receiver for receiving fluid discharged from said compressor, unloading means for said compressor, venting means for said receiver, a power driven mechanism adapted to be driven by said power unit, means for controlling the connection of said power driven mechanism in driven relation with said power unit, and means operatively connected to said last mentioned means and operative simultaneously therewith for controlling said unloading means and said venting means.

11. In combination, an internal combustion engine, a compressor connected for drive by said engine, means for controlling the speed of said engine including a pressure fluid controlled throttle valve, fluid actuated unloading means for said compressor, means including a pilot valve responsive to a predetermined compressor discharge pressure for supplying pressure fluid to effect closure of said throttle valve and for supplying pressure fluid to said unloading means, a hoist adapted to be connected in driving relation with said engine, a manually operated clutch for connecting said hoist in driven relation with said engine, and means operatively connected to said clutch and operating simultaneously therewith for supplying fluid under pressure to said unloading means.

12. In combination, a power unit, a compressor connected for drive by said power unit, a receiver for receiving fluid discharged from said compressor through a discharge conduit, a check valve in said discharge conduit permitting fluid flow toward said receiver and preventing fluid flow in the opposite direction, fluid actuated unloading means for said compressor, means responsive to the pressure in said discharge conduit for controlling the flow of pressure fluid to said unloading means, a power driven mechanism adapted to be driven by said power unit, manually operated means for controlling the connection of said power driven mechanism in driven relation with said power unit, and means operatively connected to said last mentioned means and operative therewith for simultaneously venting said discharge conduit and supplying fluid to said unloading means.

13. In combination, a power unit, a compressor connected for drive by said power unit, a receiver for receiving fluid discharged from said compressor through a discharge conduit, a check valve in said discharge conduit permitting fluid flow toward said receiver and preventing fluid flow in the opposite direction, fluid actuated unloading means for said compressor, means responsive to the pressure in said discharge conduit between said compressor and said check valve for controlling the flow of pressure fluid to said unloading means, manually controlled valve means for venting said discharge conduit between said compressor and said check valve,

a power driven mechanism adapted to be driven by said power unit, manually operated means for controlling the connection of said power driven mechanism in driven relation with said power unit, valve means for controlling a supply of fluid under pressure to said unloading means, and means operatively connected to said manually operated means and operative simultaneously therewith for actuating said manually controlled valve means and said last mentioned valve means.

14. In combination, an engine, a compressor driven by said engine and having unloading means controlled by compressor discharge pressure, a receiver, a discharge connection between the compressor and the receiver, a hoist, clutch means between the compressor and hoist, controlling means for said clutch means, and means actuated upon movement of said clutch controlling means to connect said hoist for drive to apply an auxiliary unloading force to said unloading means.

15. In combination, an engine, a compressor driven by said engine and having unloading means controlled by compressor discharge pressure, a receiver, a discharge connection between the compressor and the receiver, a hoist, clutch means between the compressor and hoist, controlling means for said clutch means, means actuated by movement of said clutch controlling means to connect said hoist for drive to apply an auxiliary unloading force to said unloading means, and means for relieving said unloading means from its normal compressor discharge pressure control while said hoist is connected to said compressor.

16. In combination, an engine, a compressor driven by said engine and having unloading means controlled by compressor discharge pressure, a receiver, a discharge connection between the compressor and the receiver, a hoist, clutch means between the compressor and hoist, controlling means for said clutch means, means actuated by movement of said clutch controlling means to connect said hoist for drive to apply an auxiliary unloading force to said unloading means, and means including receiver venting means for relieving said unloading means from its normal compressor discharge pressure control while said hoist is connected to said compressor.

17. In combination, an engine, a compressor driven by said engine and having unloading means controlled by compressor discharge pressure, a receiver, a discharge connection between the compressor and the receiver, valve means in said discharge connection for preventing the flow of fluid from said receiver toward said compressor, a hoist, clutch means between the compressor and hoist, controlling means for said clutch means actuated by movement of said clutch controlling means to connect said hoist for drive to apply an auxiliary unloading force to said unloading means, and means for relieving said unloading means from its normal compressor discharge pressure control while said hoist is connected to said compressor, said relieving means including discharge connection venting means between said valve means and said compressor.

18. In combination, a power unit, a pump driven by said power unit, means operative upon the supply of operating medium thereto for effecting a slowing down of said power unit, means operative when pump discharge pressure attains to a predetermined value for effecting a supply of operating medium to said means for effecting a

slowing down of said power unit, apparatus adapted to constitute a further load for said power unit, means for connecting said apparatus to said power unit for drive by the latter, operating means for said connection effecting means, and means rendered operative whenever said operating means is caused to effect connection of said apparatus with said power unit for effecting discontinuation of the subjection of said means for effecting a slowing down of the power unit to operating medium if such a subjection exists at the time of such connection.

19. In combination, a power unit, a pump driven by said power unit and having unloading means operable upon the supply of operating medium thereto to effect unloading of the pump, a power unit speed controlling mechanism having a controlling device operative upon the supply of operating medium thereto to effect the slowing down of the power unit, pump discharge pressure responsive means operative when pump discharge pressure reaches a predetermined value for effecting the supply of operating medium to effect unloading of the pump by said unloading means and the slowing down of the power unit by said power unit speed controlling mechanism, apparatus adapted to constitute a further load for said power unit, means for effecting connection of said apparatus for drive by said power unit, operating means for said connection-effecting means, and means operated whenever said connection-effecting means connects said apparatus for drive by the power unit for freeing said controlling device from the action of operating medium if operating medium is being supplied thereto when said apparatus is connected for drive by said power unit.

20. In combination, a power unit, a pump driven by said power unit and having fluid operated unloading means, a power unit speed controlling device having a fluid operated control mechanism, pump discharge pressure responsive means for effecting fluid supply for effecting operation of said unloading means to unload the pump and of said power unit speed controlling device to slow down said power unit when pump discharge pressure reaches a predetermined value, a hoist, means for effecting connection of said hoist for drive by said power unit, operating means for said connection-effecting means, and means connected for operation with said connection-effecting means for interrupting the supply of fluid to said power unit speed controlling device under the control of said pump discharge pressure responsive means when said hoist is connected for drive by said power unit.

21. In combination, a power unit, a pumping apparatus connected for drive by said power unit, pump discharge pressure responsive means operative upon the attainment of a predetermined pump discharge pressure for unloading said pumping apparatus and slowing down said power unit, a separate mechanism adapted to be driven by said power unit, means for effecting a connection of said separate mechanism in driven relation with said power unit, and means made effective whenever said mechanism is connected in driven relation with said power unit for effecting unloading of said pumping apparatus if it be loaded at the time and for rendering said means for slowing down said power unit ineffective if it be maintaining said power unit slowed down at the time.

22. In combination, a power unit, a pumping apparatus connected for drive by said power unit,

pump discharge pressure responsive means, means controlled by said pump discharge pressure responsive means for effecting unloading of said pumping apparatus when pump discharge pressure attains a predetermined value, means controlled by said pump discharge pressure responsive means for slowing down said power unit when pump discharge pressure attains to said predetermined value, another mechanism adapted to be driven by said power unit, means for effecting a connection of said other mechanism in driven relation with said power unit, and means made effective whenever said other mechanism is connected in driven relation with said power unit for effecting unloading of said pumping apparatus if it be loaded at the time and for rendering said means for slowing down said power unit ineffective even though said pump discharge pressure responsive means be at the time effecting slowing down of said power unit.

23. In combination, a power unit, a pumping apparatus connected for drive by said power unit, a pressure responsive device for controlling the supply of operating fluid to said power unit, pressure responsive unloading means for said pumping apparatus, means for conducting pressure fluid to said pressure responsive device and to said unloading means, means operative at a predetermined pump discharge pressure for supplying pressure fluid to said fluid conducting means, valve means movable to effect an interruption of the delivery of fluid to said conducting means and the venting of fluid from said conducting means, means for conducting fluid under pressure from a separate source to said unloading means, valve means for controlling the flow of pressure fluid through said last mentioned means, another mechanism adapted to be driven by said power unit, manually operated means for controlling the connection of said other mechanism in driven relation with said power unit, and means connected for operation with said manually operated means and adapted to effect actuation of said valve means to positions for effecting an interruption of the flow of fluid to said pressure responsive device and for supplying fluid to said unloading means when said manually operated means is operated to connect said other mechanism in driven relation with said power unit.

24. In combination, a power unit, a compressor connected for drive by said power unit, a pressure responsive device for controlling the supply of operating fluid to said power unit, pressure responsive unloading means for said compressor, means operative at a predetermined maximum compressor discharge pressure for supplying pressure fluid to said pressure responsive device, said pressure fluid supplying means including a valve for controlling the flow of operating fluid relative to said pressure responsive device, means including a valve for supplying fluid under pressure to said unloading means, another device adapted to be driven by said power unit, a clutch mechanism for controlling the connection of said other device to be driven in driven relation with said power unit, and means so constructed and arranged that upon operation of said clutch mechanism to connect said other device to be driven in driven relation with said power unit said valves are disposed in positions for venting fluid from said pressure responsive device and for supplying fluid under pressure to said unloading means.

25. In combination, a power unit, a compressor connected for drive by said power unit, a pressure

responsive device for controlling the supply of operating fluid to said power unit, means operative at a predetermined discharge pressure of said compressor for supplying pressure fluid to said pressure responsive device, a power driven mechanism adapted to be driven by said power unit, means for controlling the connection of said power driven mechanism in driven relation

with said power unit, valve means for controlling the supply of pressure fluid to said pressure responsive device, and means including a manually operated element for controlling both the operation of said valve means and said connection controlling means.

RALPH E. LAMBERTON.

CERTIFICATE OF CORRECTION.

Patent No. 2,334,207.

November 16, 1943.

RALPH E. LAMBERTON.

It is hereby certified that error appears in the printed specification of the above numbered patent requiring correction as follows: Page 1, second column, line 29, for "mechanism" read --mechanisms--; page 2, first column, line 12, after "detail" insert --central--; line 64, for "member" read --manner--; page 4, second column, line 38, after "throwing" strike out "that"; page 6, first column, line 32, for "the" before "present" read --this--; page 7, first column, line 14, claim 10, for "crankhsaft" read --crankshaft--; and second column, line 60, claim 17, for "means actuated" read --means, means actuated--; and that the said Letters Patent should be read with this correction therein that the same may conform to the record of the case in the Patent Office.

Signed and sealed this 15th day of February, A. D. 1944.

(Seal)

Henry Van Arsdale,
Acting Commissioner of Patents.
